V. O'CONNELL

FUNNEL

Filed Aug. 23, 1922

INVENTOR
V. O'Connell

BY

M. Blaine
ATTORNEY

UNITED STATES PATENT OFFICE.

VINCENT O'CONNELL, OF NEW YORK, N. Y.

FUNNEL.

Application filed August 23, 1922. Serial No. 583,684.

To all whom it may concern:

Be it known that I, VINCENT O'CONNELL, a citizen of the United States, residing at New York, in the county of New York and State 5 of New York, have invented certain new and useful Improvements in Funnels, of which the following is a specification.

This invention relates to improvements in that class of apparatus used in filling containers, as bottles, jugs and like objects, having relatively small openings, from a supply source, such devices being known as funnels.

The principal object of this invention is to provide a funnel with means for closing the 15 passage, leading from the upper body or receiving portion to the hollow dispensing stem, until the apparatus is positioned in operative position.

An equally important purpose is in the 20 provision of means for closing the same passage automatically when the receiving vessel has been filled thereby avoiding overflow and consequent waste.

These objects are attained by the novel 25 construction and arrangement of parts hereinafter described and shown in the accompanying drawing, forming part of this disclosure, and in which:—

Figure 1 is a top plan view of a funnel 30 made in accordance with the invention.

Figure 2 is a partial side elevational, partial sectional view of the same.

Figure 3 is an enlarged fragmentary longitudinal sectional view of the same, the 35 valve being shown in an open position.

Figure 4 is a similar view of the same but showing the main valve in a closed position.

Figure 5 is a fragmentary sectional view 40 of the sleeve and valve seats in detail.

Figure 6 is a transverse sectional view taken on line 6—6 of Figure 4.

The invention, as shown in the drawing, includes a body portion 10, cup shaped or conical as preferred, having a beaded rim 11 45 and provided with a stout handle 12, the body being supplied with liquid from any convenient source and in any manner, as from a tube, dipper or other container direct.

A sleeve 14 extends down from the bottom 50 of the body 10, the lower, inner portion of which is recessed to receive a removable strainer 15, consisting of a perforate disc, and the upper part of the sleeve bushing 16

is bevelled to produce a conical seat 17. A similar seat 17' being formed in the bottom 55 of the bushing.

Loosely fitting the bore of the sleeve bushing 16 is a cylindrical plug 18 having a conical head 19 adapted to fit the seat 17 and co-operating with it to constitute a gravity 60 operating valve.

Immediately below the head 19, a plurality of holes 20 are drilled transversely in the plug 18, these holes communicating with the upper end of an axial opening 21 leading 65 from its bottom, which is slightly reduced and provided with a screw-thread 22.

A tube 23, constituting the spout or dispensing stem, having its exterior diameter agreeing with that of the plug 18, is screw-threaded interiorly at its upper end to receive 70 the threaded portion 22, both plug and tube being slidable in the bushing 16.

Fixed on the tube 23, near its upper end, is a bevelled collar 24 limiting the upward 75 movement of the tube by contact with the valve seat 17' of the sleeve forming a liquid tight joint when in contact effectually preventing leakage of the funnel when resting on a bottle and secured to the lower side of 80 the collar is a disc 25, containing a plurality of perforations 26 and having radial undulations 27 formed in its surface.

Due to the weight of the plug, tube and plate, the head 19 will be held by gravity 85 against the valve seat 17 thus preventing flow of liquid from the funnel body.

Upon entering the tube into a container having a relatively small mouth, as a bottle, until the outstanding disc 25 rests upon the 90 mouth, the tube will be raised within the sleeve and the head or valve 19 from its seat 17, permitting the liquid to flow past, enter the plug holes 20 and by them be conducted to the plug opening 21, which being 95 in open communication with the interior of the tube 23, the liquid will be directed into the container to be filled so long as the disc is held in a raised position and the body of the funnel kept supplied.

Conversely, upon raising the funnel so as to permit the tube to slide down in the sleeve, the valve head reseats itself and closes the flow of liquid, thus fulfilling one object of 100 the invention.

The second object is attained in the fol-

lowing manner. A pin 28 is passed through the tube 23 near its lower end, or other equivalent stop provided, limiting the downward movement of a thin, very light float tube 29, of considerable less diameter than the interior of the tube 23, and provided with longitudinal guide ribs 30 by which it is maintained substantially central.

The float tube 29 is open at its lower end and formed with a closed cone 31 at its upper end, the same being adapted to make contact with a corresponding coned valve seat 32 formed in the lower end of the plug 18 at the entrance to the opening 21, the arrangement being such that when the float tube rests against the stop 28, the passage for liquid will be open, but when the float tube is raised, the passage will be closed.

In operation, as the float tube 29 is air and water tight, air entering the lower, open end will be compressed as the liquid rises in the container to a point above the stop, causing the tube to rise and eventually shut off the flow automatically just prior to the

liquid reaching the level of the container 25 mouth, whereupon the funnel may be raised, bringing the other valve into operation, with substantially no spilling, overflow or loss.

Having thus described my invention and set forth the manner of its construction, application, purposes and use, what I claim as new and desire to secure by Letters Patent, is:—

A valve seat comprising a fixed annulus having a bore and conical seats converging 35 toward the bore on each side of the annulus, a valve plug slidable in the mentioned bore and having an axial recess with ports normally closed by the wall of the bore, a conical head on said plug suited to engage in one 40 of the valve seats, and a ring fixed on said plug having a conical portion adapted to seat in the other valve seat when the plug is moved in the annulus to present the ports therebeyond.

In witness whereof I have affixed my signature.

VINCENT O'CONNELL.
